LIQUID COOLER

William D. Drysdale, Mount Clemens, Mich., assignor to Walter J. Sugden, West Roxbury, Mass.

Application November 2, 1934, Serial No. 751,180

3 Claims. (Cl. 62—141)

This invention relates to mechanically refrigerated liquid coolers of the inverted bottle type. The invention aims to provide a cooler which shall be small, compact and light so that it may be moved about easily and placed on tables, filing cabinets and the like. The invention also aims to provide a cooler which shall be highly efficient and economical and which shall minimize conduction and radiation of heat from the bottle into the liquid reservoir.

The invention will readily be understood by reference to the following description when taken in connection with the accompanying drawings of one specific embodiment thereof, while its scope will be pointed out more particularly in the appended claims.

In the drawings:

Fig. 1 is a plan of a liquid cooler embodying the invention as it appears without the bottle;

Fig. 2 is an elevation of the same with the bottle in place, a portion of the bottle being broken away;

Fig. 3 is a vertical, sectional view of the upper portion of the cooler on an enlarged scale on line 3—3 of Fig. 1;

Fig. 4 is a vertical, sectional view of the lower portion of the cooler on an enlarged scale on line 4—4 of Fig. 1;

Fig. 5 is a conventionalized, perspective view illustrating the compressor-condenser-expander circuit;

Fig. 6 is a horizontal, sectional view on an enlarged scale on line 6—6 of Fig. 2;

Fig. 7 is a vertical, sectional view on line 7—7 of Fig. 6 showing the location and mounting of the expansion valve;

Fig. 8 is a plan of the upper and lower platforms and the framework connecting them disassociated from the other parts;

Fig. 9 is an elevation of the parts shown in Fig. 8;

Fig. 10 is a horizontal, sectional view on line 10—10 of Fig. 9;

Fig. 11 is a vertical, sectional view on an enlarged scale on line 11—11 of Fig. 10;

Fig. 12 is a horizontal, sectional view on an enlarged scale on line 12—12 of Fig. 9;

Fig. 13 is a vertical, sectional view on an enlarged scale on line 13—13 of Fig. 9;

Fig. 14 is an elevation of the fan shroud or baffle; and

Fig. 15 is a horizontal, sectional view on line 15—15 of Fig. 14.

Referring to the drawings and to the embodiment of the invention illustrated therein by way

of example, there is shown (see Figs. 1 and 2) a liquid cooler comprising a housing 20 having an opening 22 at the top for the downward insertion of the neck 24 of a bottle 26. The bottle is conveniently supported by a rubber ring 28 (see 5 Fig. 3) which is seated in an annular recess 30 about the opening 22. This ring is provided with one or more notches 32 for the equalization of air pressures within and without the space at the upper portion of the cooler, and, as shown, 10 the ring is notched at the bottom as well as at the top so that if it should accidentally be inverted there will still be the desired equalization of pressures.

Within the upper portion of the housing is a 15 reservoir 34 for the liquid to be cooled, said reservoir having an opening 36 at the top to receive the bottle neck. Leading from the lower portion of this reservoir is an outlet conduit 38 which leads to a faucet 40 from which the liquid is 20 drawn for use. Within the reservoir is a refrigerant expander, herein a coil 42, having a suitable number of convolutions and appropriately supported as by three brackets 44 which are secured to the bottom of the reservoir. Also within the reservoir is a cup 46 which receives the bottle neck and is conveniently supported by the upper portion of the reservoir as by providing the cup with an outwardly directed annular projection 48 which rests upon an annular seat 50 presented by the reservoir. This cup has an outlet 52 which leads from its interior into the reservoir desirably at a point remote from the outlet conduit 38 so that the liquid issuing from the outlet 52 is compelled to pass over a considerable area of the coil before reaching the outlet conduit. The cup is preferably made of glazed porcelain which, being a good non-conductor of heat, minimizes conduction of heat from the bottle into the reservoir and segregates in the reservoir a body of water 25 which is thoroughly cooled by the expansion coil 30

before passing to the faucet.

The porcelain cup is easily removable to enable it, as well as the interior of the reservoir, to be thoroughly cleansed. In practice, the reservoir will be made of copper and it, as well as the coil 42, will be coated with tin to prevent corrosion and to afford less opportunity for accumulation of unsanitary deposits. In the example shown, the body of the reservoir is provided at its upper portion with an annular seat 54 in which is seated a downwardly directed marginal portion 56 of a ring 58 in which the opening 36 is 35 formed. After the coil and other parts have been assembled within the reservoir, the ring 58 is 40 50 55 60 65 70 75 80 85 90 95 100 105 110 115 120 125 130 135 140 145 150 155 160 165 170 175 180 185 190 195 preferably secured to the body of the reservoir as by soldering the marginal portion of the ring to the upper edge of the reservoir body.

It will be observed that the opening 22 is above and considerably smaller in diameter than the opening 36 in the reservoir 34, and it follows that there is little, if any, danger of moisture entering the space between the reservoir and the housing, owing to the overlapping relationship between the margins of the openings 22 and 36. This space between the reservoir and the housing is filled with a body of insulating material 60 to minimize conduction of heat from the exterior of the housing to the reservoir. This insulating material is not at all likely to be injured by moisture, owing to the relative arrangement of the openings 22 and 36. In practice, the cup 46 is made of white, glazed porcelain which reflects the light, and therefore facilitates the downward insertion 20 of the bottle neck into the cup without danger of spilling water from the bottle.

In the embodiment shown, the reservoir is provided with feet 62 which support and elevate the bottom of the reservoir above the top of a body 64 of appropriate insulating material, the character of which preferably is such that it can be molded or pressed into the form desired, with recesses 66 in its upper face to receive the feet 62 and thereby to hold the reservoir against horizontal displacement. The body 64 is also conveniently recessed as at 68 to receive a portion of the outlet conduit 38 which leads from the reservoir to the faucet. The bodies of insulation 60 and 64 together provide a thorough jacketing 30 of the reservoir and minimize conduction of heat to the interior of the reservoir.

As herein shown, the insulating body 64 rests upon, is supported by, and is secured to an upper platform 68, the securing means herein shown comprising cap screws 70 whose upper ends are threaded into the feet 62 and whose lower ends are provided with heads 72 received in recesses 74 in the underside of the platform. In the present example, the platform is conveniently made of 40 laminated wood.

Below the upper platform is a lower platform 76 (see Fig. 9), and between these platforms is a machinery compartment 78 which is closed at its sides by the housing 20, the latter being secured to the uprights as by screws 82 (see Fig. 2) 50 threaded into openings 84 (see Fig. 9) in the uprights. In the present example, the uprights diverge upwardly and the sides of the housing correspondingly diverge and at the corners snugly 55 fit the uprights, as a result of which the weight of the housing and that of the superimposed bottle of water is not borne by the screws 82 but is distributed along the diverging surfaces of the uprights. This is one factor in securing great 60 strength and compactness with light weight.

In the present example, the uprights are supported by feet 86 conveniently made of sheet metal and herein provided with rubber pads 88 to rest upon the table or the support, these pads being conveniently secured to the feet as by screws 90 (see Fig. 11) threaded into horizontal flanges 92 presented by the feet. The feet are conveniently secured to the uprights as by screws 94 (see Fig. 13) which extend through flanges 96 70 presented by the feet, and into threaded openings 98 in the lower ends of the uprights.

The upper platform is conveniently supported on the uprights as by providing each of the latter with pairs of inwardly directed projections 75 100 above and below the platform, and spaced

apart a sufficient distance to enable the platform to fit snugly between them, and the platform is secured to the upright by pairs of screws 102. The lower platform is secured to the upright with a similar fashion by providing the upright with like pairs of inwardly directed projections 104 between which the platform is snugly received, and in this case also, the uprights are secured to the platform by pairs of screws 106.

Thus the platforms, the uprights and the feet 10 constitute a light but exceedingly strong framework which not only sustains the housing and the bottle of water and the reservoir in the described manner, but also affords a compartment and support for the machinery of the mechanical refrigerating apparatus now to be described.

Reference has been made to the fact that the expansion coil 42 within the reservoir 34 is a part of a compressor-condenser-expander circuit. The remainder of this circuit will now be described, reference being had to Fig. 4 wherein there is shown within the machinery compartment 78 a motor-compressor unit 108 of the so-called sealed unit type wherein a compressor and an electric motor which drives the same is sealed 25 within a housing. It is deemed unnecessary further to describe this unit other than to point out that the compressed refrigerant leaves the unit through a pipe 110 which, as shown in Fig. 5 in a somewhat conventional fashion, leads to a 30 condenser 112 through which the compressed refrigerant passes and is condensed, after which it is conducted by a pipe 114 to a liquid reservoir 116 whence it is conducted by a pipe 118 which leads upwardly through the upper platform 68 35 and insulating body 64 into the reservoir 34 where it is connected to an expansion valve 120 from which the liquid refrigerant is released in the form of a spray through an outlet 122 connected to the expansion coil 42. This expansion 40 valve is not new in and of itself, but may be one of several commercially available types, the one shown being a well known unit made by Fedders Manufacturing Company. However, according to the present invention, this expansion 45 valve is located within the water reservoir, and this location is advantageous not only because it provides a compact construction, but because this location decreases the efficiency of the machine, and because moisture, which is bound to collect on the outside of the expansion valve, drips into the reservoir where it can do no harm. If this expansion valve were placed on the outside, the dripping of moisture would be serious. The expansion valve is conveniently supported in the 50 reservoir as by providing the ring 58 of the reservoir with an opening 124 which receives a neck 126 presented by the expansion valve, and on to this neck is threaded a cap nut 128 which is screwed against a gasket 130 about the opening, 60 as shown in Fig. 7.

The expansion valve discharges the refrigerant in the form of a spray into the expansion coil and the evaporating action cools the coil and therefore the water within the reservoir. After passing through the several convolutions of the coil, the refrigerant is conducted by a pipe 132 to the exterior of the reservoir (see Fig. 6) and this pipe leads downwardly through the insulating body 64 and the upper platform 68 (see Fig. 5) to the 70 machinery compartment where it is connected to an inlet 134 leading into the compressor unit 108. This completes the circuit.

The control of the motor of the compressor unit is vested in a switch 136 within the ma- 75

achinery compartment. This switch is not novel but may be one of several commercially available types, the one employed in the present example being made by Cutler-Hammer, and it embodies within itself a bellows or accordion-like thermostatic element which is connected by a capillary tube 138 which leads upwardly through the upper platform 68 and insulating body 64 and into the reservoir 34 where it terminates in a bulb 140 which, as best shown in Fig. 3, is conveniently mounted within the reservoir as by being secured to one of the brackets 44 by a clamp 142 and a screw 144.

Assuming that we start with a water temperature of 75° F. in the reservoir, this temperature causes the closing of an electric circuit and the switch 136 operates to start the compressor unit. If it be desired to keep the water in the reservoir at temperatures of from 42° F. to 47° F., the setting of the switch is such that the machine will run until the temperature of the water in the reservoir reaches 42° F. When this temperature is reached, the compressor unit will stop and will remain out of operation until the temperature of the water in the reservoir rises to 47° F., whereupon the switch operates to re-start the compressor unit. The temperatures given are, of course, merely by way of example.

Returning now to the compressor unit, the latter, as shown in Fig. 4, is housed within the machinery compartment 78 and is appropriately mounted on the lower platform 76 as by a suitably cushioned mounting 146. Also within this compartment is the condenser 112, and associated with this condenser is a fan 148 which is driven by a motor 150 mounted on a bracket 152 secured to the platform 76 by bolts 154 which extend through rubber grommets 156 to provide a cushioned support for the bracket. With this fan is associated a baffle 158, best shown in Figs. 14 and 15, which is in the nature of a partition extending entirely across the machinery compartment from side to side and has an opening 160 within which the fan rotates. The purpose of this baffle is to increase the efficiency of the fan by compelling all of the air to pass through the restricted opening 160 about the fan.

The platform 76 is provided with two openings 162 and 164 (see Fig. 4) on opposite sides of the group of parts comprising the condenser, the fan and the baffle, as a result of which rotation of the fan draws air from the exterior of the housing upwardly through the opening 162 through the condenser and through the baffle whence it is directed against the compressor unit, passes about the top, sides and bottom of the latter, and then escapes through the opening 164 to the outer atmosphere. In this way the condenser is cooled to assist in the liquefaction of the refrigerant, and the current of air also cools the compressor unit.

Having thus described one embodiment of the invention, but without limiting myself thereto, what I claim and desire by Letters Patent to secure is:

1. In a liquid cooler of the inverted bottle type, the combination of a housing having an opening at the top for the downward insertion of the bottle neck, a reservoir within said housing for the liquid to be cooled, said reservoir having an opening at the top to receive the bottle neck, a liquid outlet conduit leading from said reservoir to the exterior of said housing, a refrigerant expansion coil disposed within said reservoir to cool the liquid in the latter, and a cup within and spaced from the internal surface of said reservoir to receive the bottle neck, said cup having an outlet into said reservoir, said cup outlet being remote from said outlet conduit, thereby to compel the liquid to flow over a considerable area of said coil before reaching said outlet conduit, and said coil being disposed in the space between the internal surface of said reservoir and the external surface of said cup.

2. In a liquid cooler, the combination of an inverted bottle having a downwardly directed neck, a primary reservoir about and spaced from the sides and bottom of said neck and freely communicating with the interior of said bottle, said reservoir being provided with an outwardly directed projection, a secondary reservoir about and spaced from the sides and bottom of said primary reservoir and freely communicating with its interior, said secondary reservoir presenting about said primary reservoir a support on which said outwardly directed projection rests, said secondary reservoir having an upper wall which extends inwardly beneath and supports said outwardly directed projection, a housing about and spaced from said secondary reservoir and having an opening through which said primary reservoir may be withdrawn upwardly, said housing presenting about said opening a support for said bottle, and thermal insulation in the space between said secondary reservoir and said housing.

3. In a liquid cooler, the combination of an inverted bottle having a downwardly directed neck, a primary reservoir about and spaced from the sides and bottom of said neck and communicating at all times with the interior of said bottle, said reservoir having an outwardly directed projection, a secondary reservoir about and spaced from the sides and bottom of said primary reservoir and communicating therewith, said secondary reservoir presenting an inwardly directed support upon which said outwardly directed projection rests, and a housing about said secondary reservoir, said housing having an opening through which said primary reservoir may be withdrawn upwardly, and having about said opening a support for said bottle.

WILLIAM D. DRYSDALE.
